UNITED STATES PATENT OFFICE.

ALVIN DAHL, OF NICHOLSON, PENNSYLVANIA, ASSIGNOR TO FRANK M. TALBOT, OF GLEN RIDGE, NEW JERSEY.

DEVICE FOR OPERATING DUMPING-BUCKETS.

1,145,564.

Specification of Letters Patent.

Patented July 6, 1915.

Application filed August 22, 1913. Serial No. 739,209.

To all whom it may concern:

Be it known that I, ALVIN DAHL, a citizen of the United States, residing at Nicholson, in the county of Wyoming and State of Pennsylvania, have invented certain new and useful Improvements in Devices for Operating Dumping-Buckets, of which the following is a specification, reference being had therein to the accompanying drawing.

10 My invention refers to a dumping device for buckets, more particularly large buckets designed to contain large quantities of earth, clay, broken stone or other material.

15 The object of the invention is to enable the buckets or receptacles of this kind to discharge their contents with the expenditure of as little power as possible and by a simple and efficient trip mechanism which is easily and quickly operated.

20 The invention, therefore, consists essentially in the construction, arrangement and combination of the various parts, substantially as will be hereinafter described and then more particularly pointed out in the 25 claims.

30 In the accompanying drawing illustrating my invention: Figure 1 is a side elevation of my improved dumping device for buckets and receptacles. Fig. 2 is another side elevation viewed from a point opposite to that in Fig. 1. Fig. 3 is a partial sectional plan view showing the locking pin for the latch and the parts cooperating therewith. Fig. 4 is a side elevation of the same.

35 Similar characters of reference designate corresponding parts throughout the different figures of the drawing.

1 denotes a vertical bar, having on its lower end a hook 2, the latter being designed 40 to engage the bail or handle 26 of the dumping bucket 4. Alongside of the hook bar 1 is another bar 5, preferably only about half the length of the hook bar 1, and secured to said hook bar 1 by means of metal clamps 45 or straps 6, which are securely fastened to each other by means of bolts at 7 or in any other convenient way. Thus the two bars 1 and 5 are connected together in a rigid and solid fashion. They may, if desired, be built 50 as a single bar instead of two separate bars. The upper ends of these bars 1 and 5 are suitably perforated or provided with eyes for the attachment of chains 8 and 9 there-

to, which chains are also attached to a link 10 that is adapted to be engaged by a hook 55 or other appliance operated by the crane which lifts the entire bucket mechanism.

11 designates a latch made in general right-angled form and pivotally supported at 12 in the lower end of the latch-supporting bar 5. This latch 11 has a bucket-supporting arm 13, also a locking arm 14. The hook bar 1, at a point not far from the pivotal point 12 of the latch 11, is provided with a horizontal projection 15, in which is 60 a vertical swivel bolt 16; and also said hook bar 1 is provided with a projection 17 parallel to the projection 15 and independent thereof, which projection 17 is fashioned in its upper edge with an indent or notch 18. 65 The projections 15 and 17 are separated a short distance from each other, and between them the locking arm 14 of the latch 11 is adapted to drop when the latch is in its operative position as shown in Fig. 1, said 70 locking arm 14 being then vertical while the supporting arm 13 is horizontal. The swivel bolt 16 is provided on its lower end with a nut 19; and to its upper end is pivoted a pin 20. Obviously, therefore, this pin can 75 be raised up and down vertically by hand, and it can also be swung around in a horizontal plane by an easy revolution of the swivel bolt 16. Thus the pin 20 can occupy a position like that shown in Fig. 2 where it 80 is swung around out of the way, or it can be caused to pass over and bridge across the gap between the two projections 15 and 17, with its free end dropping into and engaging the notch 18, in which position said pin 85 90 holds the locking bar 14 firmly in the position shown in Fig. 1, and prevents it from lifting into the position shown in Fig. 2, for obviously if the weight of the bucket rests on the arm 13 of the latch 11, the effect 95 will be to force the locking arm 14 with a strong pressure against the horizontal pin 20 and thus keep the latch in its operative position as shown in Fig. 1.

Having thus described the way in which 100 the latch serves to uphold a leaded bucket while it is being lifted and carried about from one point to another, it now becomes necessary to explain the mechanical details by means of which the dumping or releasing 105 of the bucket is easily and quickly effected,

as this is the important object of the invention, and it is necessary that it should be accomplished by mechanism whose details are simple and yet effective. To this end I 5 employ a trip lever which is pivoted at 22 to the side of the notched projection 17. The trip lever 21, at its pivoted end, is formed with a rounded enlargement which is notched at 23 for the purpose of receiving the bolt 20 in said notch. These particular features are indicated in Fig. 1 where it is seen that the pin or bolt 20, when it lies in the notch 18 in the projection 17, will also be engaged by the notch 23 in the pivoted end of the lever 21. The form of the notch 23 as also the form of the pivoted end 21 may vary within considerable limits. It is important that this lever 21 should have on the other side of its pivot 22 a short 10 projection which can rest beneath the pin 20, so that when the free end of the lever 21 is pulled down, the pin 20 will be raised and lifted out of the notch 18 for the purposes of setting free the locking bar 14 of 15 the latch 11, and it is also important that the notch 23 should lock the pin 20 until it is time to dump the bucket. A spring 24 is attached to the lever 21 and also to the hook bar 1, or to one of the clamps 6, and serves 20 to hold the lever 21 in its upper position, as shown in Fig. 1, and to return it to that position after a releasing of the parts has been effected at each dumping operation, so that the spring thus keeps the lever 21 and its 25 notched end 23 in position to allow a locking engagement of the notch with the pin 20 to be easily made from time to time. It is desirable that the notch 23 should be employed rather than merely a short end of the lever 30 21 beyond the pivot, because the notch furnishes an inner wall that will bear against the pin 20 as the spring pulls up the lever 21 and will thus keep the one side of the notch in proper position under the pin 20 35 at all times when the parts are actively related for service. The cable or cord 25, which is attached to the outer end of the trip bar 21, may be any suitable kind of a rope, cable or cord running to some point 40 where it can be easily operated, and it will be found that only a slight expenditure of power will be necessary to actuate the tripper sufficiently to disengage the pin 20 from the notch 18. 45

50 The form of bucket with which my improved release device is generally used is preferably of a form having two bails at the top and twin doors opening at the bottom. One of the bails is like that shown at 55 26 which is attached to the top of the bucket 4 and is permanently engaged by the hook 2. The other bail 3, which rests on the latch arm 13 when the bucket is being loaded and carried, is connected by suitable levers 27, 60 as shown, to the doors 28 at the bottom of

the bucket. Obviously when the bail 3 is released, the weight inside of the bucket will pull down the bail through the said levers, and the doors will automatically open and discharge the contents of the bucket. The 70 parts can all be reset for another filling of the bucket by simply lifting the bail and placing it again upon the latch arm 13, after the locking arm 14 has been locked in place by the pin 20 and the tripper 21 set in place 75 for further action in dumping when required.

Many changes in the precise construction and arrangement of the various parts may be made without exceeding the invention, 80 and I reserve the liberty of making all such changes as may in practice be found desirable or necessary.

Having thus described my invention, what I claim as new and desire to secure by Letters Patent, is:

1. In a device of the character described, the combination with a bucket having doors and a hook for supporting said bucket, of a pivoted latch for the bucket doors, said latch 90 having a locking arm and also a bucket-engaging arm, means for restraining said locking arm when the latch is in its operative position, consisting of a swivel device and a pin pivoted thereto so as to be adjustable in two directions, and means for releasing said pin consisting of a pivoted trip lever engaging the pin.

2. In a device of the character described, the combination with a bucket having doors and means for engaging and supporting said bucket, of a pivoted latch carried by said means, said latch having a bucket-engaging arm and also a locking arm, a swivel device, a pin pivoted thereto so as to be adjustable in two directions, said pin having the function of holding the locking arm in position when the latch serves to hold the bucket doors closed, and a tripper for said pin consisting of a pivoted lever notched to engage 105 the pin.

3. In a releasing device of the character described, the combination of a bucket having dumping doors and a hook for supporting said bucket, a bail connected with the dumping doors of the bucket, a pivoted latch engaging said bail, said latch having also a locking arm, a swivel bolt, a pin pivoted to said swivel bolt for holding the locking arm in position when the latch keeps the dumping doors closed, and a trip lever engaging the pin.

4. In a releasing device of the class described, the combination of a hook bar, a companion latch-supporting bar, means for securing the two bars together, a latch pivoted to the latch-supporting bar and having a bucket-engaging arm and also a locking arm, a pin pivoted to a swivel device so as to be adjustable in two directions, said pin 120 125 130

serving to lock the latch arm, and means for releasing said pin consisting of a pivoted trip lever engaging the pin, together with a spring for returning the tripper after each 5 tripping action.

5. In a device of the character described, the combination of a hook bar, a latch-supporting bar, means for securing the bars together, a latch pivoted to the latch-supporting bar and having a bucket-engaging arm and also a locking arm, a swivel device, a pin pivoted thereto, and means for releasing said pin consisting of a notched trip lever pivoted adjacent to said pin.

10. 6. In a device of the character described, the combination with a bucket having a fixed bail and also dumping doors to which a movable bail is connected, means for supporting the fixed bail, a latch device pivoted to said means and having an arm engaging the movable bail and also a locking arm, means for restraining said locking arm when the dumping doors are closed, said means comprising a swivel pin and a pin pivoted thereto so as to be adjustable in two 20 directions, together with means for releasing

ing the latter pin, consisting of a pivoted trip lever engaging the pin.

7. In a release device of the character described, the combination of a hook bar, a pivoted latch having a bucket engaging arm and also a locking arm, a swivel device, a pin pivoted to said swivel device so as to be adjustable in two directions, and a notched and pivoted lever for engaging and releasing said pin.

8. In combination with a dumping bucket having a fixed bail, dumping doors and a movable bail connected to said doors, of means for engaging the fixed bail and supporting the bucket, and a pivoted latch engaging the movable bail, together with means for tripping said latch comprising a swivel pin, a pin pivoted thereto so as to be adjustable in two directions, and a notched 45 trip lever engaging said pin.

In testimony whereof I affix my signature in the presence of two witnesses.

ALVIN DAHL.
